LUNCH COUNTER STOOL

Peter Madsen, Los Angeles, Calif., assignor, by
mesne assignments, to Madsen Iron Works, a
limited partnership of California

Application December 9, 1940, Serial No. 369,151

3 Claims. (Cl. 155—134)

My invention relates to lunch counter stools or seats of the type having a seat portion supported on a pedestal which is secured to the floor, and relates in particular to a construction and cooperation of parts whereby the support of the lunch counter stool may be secured rigidly to the floor by means concealed from view and which does not require the extension of wrenches or tools within the pedestal.

It is an object of the invention to provide a lunch counter stool having a pedestal which may extend as a continuous member from a position adjacent the lower face of the seat to the surface of the floor and which may be rigidly secured to the floor without use of lag screws or the like disposed with the heads thereof visible around the base of the pedestal.

A further object of the invention is to provide a lunch counter stool having a pedestal extending as a continuous member from the seat to the floor and having a downwardly faced recess therein to receive a securing member which is attached to the floor prior to the placing of the lower portion of the pedestal thereover, there being locking means operative between the securing or anchoring member and the pedestal to lock the pedestal to the securing or anchor member in response to rotation of the pedestal.

A further object of the invention is to provide a lunch counter stool construction having an anchor member which requires a minimum of machine operation, or no machining at all, in the manufacture thereof, and which anchor member, when employed to secure the stool to the floor, is entirely concealed within a recess in the bottom of the support.

A further object of the invention is to provide a lunch counter stool having a pedestal with an enlarged lower end to form a base of artistic appearance, this base having a downwardly faced recess, and means securable to the floor in the position selected for the lunch counter stool, and having a part adapted to project into the recess when the lower part of the pedestal is placed thereover, and means for locking these parts together.

A further object of the invention is to provide an anchor member having a lower face to engage the floor and means for rigidly securing the anchor member to the floor. Above the surface of the floor the anchor member has radially projecting lugs adapted to engage lugs on a pedestal which is placed over the anchor member and to secure the pedestal rigidly in a position extending upwardly from the anchor member.

Further objects and advantages of the invention will be brought out in the following part of the specification.

Referring to the drawing which is for illustrative purposes only:

Fig. 1 is a view showing a preferred form of my invention.

Fig. 2 is an enlarged fragmentary vertically sectioned view of the lower portion of the pedestal with the anchor member therein.

Fig. 3 is a cross section taken as indicated by the line 3—3 of Fig. 2 showing the cooperating lugs of the pedestal and the anchor member in engagement.

Fig. 4 is a sectional view similar to Fig. 3 showing the lugs of the anchor member and of the pedestal disengaged.

In Fig. 1 I show a stool assembly A secured on a floor 10 in cooperative relation to a counter 11. This stool assembly includes a seat 12 and a support 13 for the seat shown in the form of a column or pedestal having at the bottom thereof a wall 14 enlarged so as to form a plate on flange 15 which is provided with a peripheral face 16 to engage the floor 10, as shown in Fig. 2. In the preferred practice of the invention, the seat is provided with a back 17 and is carried by the pedestal 13 so as to rotate around a vertical axis, there being cam means 18 tending to rotate the seat 12 into a position facing the counter 11.

In the preferred practice of the invention the pedestal 13 is cast in one continuous piece without intermediate joints. The invention makes possible the provision of an artistic appearance, and by elimination of external crevices such as would be caused by joints the maximum condition of sanitation is maintained. As shown in Figs. 2, 3, and 4, the wall 14 at the lower end of the pedestal 13 is enlarged and defines a portion of a downwardly faced recess 20 in the lower part of the pedestal 13. From the wall 14 a plurality of lugs 21 project within the recess 20 toward the vertical axis of the pedestal 13, there being spaces 22 between these lugs 21. In employment of the term "lugs" in conjunction with the numeral 21, I mean walls so formed as to have upwardly faced surfaces 23 to serve a purpose which will be hereinafter described.

Within the recess 20, and concealed thereby, there is an anchor member 24 preferably comprising a circular body 25 having an opening 26 through which a bolt 27 may be extended to secure the anchor member 24 to the floor, and having a plurality of radially projecting lugs 28 positioned in a plane above the plane of the lugs 21.

when the pedestal 13 is placed over the anchor member 24 with such anchor member 24 received in and concealed within the recess 20. As will be noted in Fig. 4, the lugs 28 of the anchor member 24 are slightly smaller than the spaces 22 between the lugs 21, so that as the pedestal 13 is placed over the anchor member 24 the lugs 21 of the pedestal may pass downward through the spaces between the lugs 28 to the positions thereof shown in Fig. 2. In the use of the term "lugs" with respect to the members 28 I mean walls so arranged on the body 25 of the anchor member 24 as to lie over and engage the upper faces 23 of the lugs 21 when the pedestal 13 is rotated in the direction indicated by the arrow 30 of Fig. 4 so as to carry the lugs 21 in anti-clockwise direction into the positions in which they are shown in Fig. 3.

The lower faces 31 of the lugs 28 slope downward in anti-clockwise direction, and the upper faces 23 of the lugs 21 are preferably sloped in a cooperative manner so that when anti-clockwise rotation of the pedestal 30 carries the lugs 21 under the lugs 28, downward pressure will be transmitted from the lugs 28 to the lugs 21 as a result of the cam action produced by the faces 23 and 31, thereby forcing the floor engaging portion or flange 15 of the pedestal 13 tightly into engagement with the floor 10. The invention also includes locking means for preventing reverse or clockwise rotation of the pedestal 13 relative to the anchor member 24, so that the pedestal 13 cannot be disengaged from the anchor member. A simple form of this locking means consists of a screw 35 threaded through the wall 14, so as to be screwed inward from the position in which it is shown in Fig. 4 into engagement with the anchor member 24, as shown in Fig. 3. The anchor member 24 provides a surface 36 faced outwardly from the central portion of the anchor member and which slopes rearward toward the axis or central portion of the anchor member 24 in the manner of a spiral, and the screw 35 is adapted to engage this sloping wall 36 whereby the reaction of the pressure of the screw 35 against the same will exert a force tending to rotate the pedestal 13 in anti-clockwise direction relative to the anchor member 24. As shown in Figs. 3 and 4 this rearwardly sloping face 36 for cooperation with the screw 35 is conveniently formed on the rearward portion of one of the lugs 28 of the anchor member 24.

To give an idea of the simplicity and economy of the combination hereinbefore disclosed, it may be remarked that in the present use of the invention the anchor member 24 has a diameter of about 4½ inches and is readily cast to the form shown. In view of the fact that it is entirely concealed when in use, it may be employed, without machining, in the natural state in which it is received from the foundry.

I claim as my invention:

1. In a stool of the character described, the combination of: a stool assembly having a seat portion and a support extending down from said seat portion, there being a downwardly faced recess in the lower end of said support; an anchor member of a size to be received in said recess so as to be concealed when therein, there being means for securing said anchor member to the floor; securing means operative between said support and said anchor member in response to

rotation of said support relative to said anchor member to secure said support to said anchor member; a wall on said anchor member having a surface which faces outwardly from the center of said anchor member, said surface being disposed so that its radial dimension from the center of said anchor member decreases in rearward direction; and screw means extending inwardly through the lower portion of said support into said recess to engage said surface of said anchor member.

2. In a stool of the character described, the combination of: a support having means at the upper end thereof to support a seat and a wall at the lower end thereof forming a floor engaging portion and a downwardly faced recess, there being lugs projecting into said recess from said wall; an anchor member for securing said support to a floor, comprising a body adapted to fit into said recess and having a lower face to engage the floor and outwardly extending lugs for engagement with said lugs of said support when said support is rotated relative to said anchor member, said lugs of said wall and of said anchor member having helically disposed faces for cooperative engagement when said support is rotated relative to said anchor member to force said floor engaging portion into tight engagement with the floor whereby the support will be rigidly secured to the floor, at least one of said lugs of said anchor member having an outwardly faced surface disposed so that its radial distance from the axis of said anchor member decreases in rearward direction; and locking screw means carried by said wall of said support in such position that it may be moved into engagement with said outwardly faced surface of the specified lug, to urge rotation of said support in a direction to cause further engagement of said lugs and to prevent rotation of said support relative to said anchor member.

3. In a stool of the character described, the combination of: a support having means at the upper end thereof to support a seat and a wall at the lower end thereof forming a floor engaging portion and a downwardly faced recess, there being lugs projecting into said recess from said wall; an anchor member for securing said support to a floor, comprising a circular body adapted to fit into said recess and having a lower face to engage the floor and lugs extending radially outwardly from the upper part thereof for engagement with said lugs of said support when said support is rotated relative to said anchor member, said lugs of said wall and of said anchor member having helically disposed faces for cooperative engagement when said support is rotated relative to said anchor member to force said floor engaging portion into tight engagement with the floor whereby the support will be rigidly secured to the floor; and locking means operative between said wall and said anchor member, said locking means comprising a screw threaded through said wall into said recess and a shoulder on said anchor member disposed so as to be abutted by said screw, the portion of said shoulder abutted by said screw being faced rearward to prevent disengaging rotation of said support from said anchor when said screw abuts said shoulder.

PETER MADSEN.
